UNITED STATES PATENT OFFICE.

REUEL H. THAYER, OF NEW YORK, N. Y., ASSIGNEE TO THAYER TELKEE CORPORATION, OF SAN FRANCISCO, CALIFORNIA, A CORPORATION OF CALIFORNIA.

KEY RING AND IDENTIFICATION TAG.

Application filed June 27, 1925. Serial No. 39,922.

This invention relates to identification means for keys and improvements in key rings.

One object of the invention is to provide a identification tag which may be permanently locked to a key so that it may be easily and quickly distinguished from other keys in the same bunch or ring.

Another object of the invention is to provide an identification tag for a key adapted to be permanently inserted between the key and the key ring, so as to afford a ready means for identifying keys of the same general shape on the ring.

Another object of the invention is to provide an identification tag which may readily be attached to a key or other object but which when once attached is locked permanently thereto.

Another object of the invention is to provide an improved type of key ring from which the keys may be easily and readily removed when desired, but will be held against accidental removal.

Another object of the invention is to provide a means to permanently identify a number of keys, and releasably hold them together in a bunch so, that any key may be removed but not without its identifying means.

Other objects and advantages of the invention will appear as the description progresses.

Referring now to the drawings which illustrate a preferred form of embodiment of my invention.

Fig. 1 is a front elevational view of an identification tag, which can be permanently fastened to any type of key and attached to any type of key ring.

Fig. 2 is a front elevational view of one of the discs forming the identification tag shown in Fig. 1.

Fig. 3 is a side sectional view of the identification tag shown in Fig. 1 taken on the line 3—3 of Fig. 1.

Fig. 4 is a perspective view of the identification tag shown in Fig. 1 showing the key holder in position to be inserted therein.

Fig. 5 is a front elevational view of a modified form of embodiment of the identification tag.

Fig. 6 is a front elevational view of the larger of the two sections of the tag shown in Fig. 5.

Fig. 7 is a rear view of the smaller section of the tag shown in Fig. 5.

Fig. 8 is a sectional side view taken on the line 8—8 of Fig. 5 and with the parts separated to show the manner of assembly.

Fig. 9 is a plan view of my improved key ring.

Fig. 10 is a plan view of a portion of the key ring shown in Fig. 9.

Fig. 11 is an elevational view of the key ring shown in Fig. 9.

Fig. 12 is a bottom view of a portion of the key ring shown in Fig. 9.

Fig. 13 is a sectional elevation taken on the line 13—13 of Fig. 9, and

Fig. 14 is an enlarged plan view of one of the identification tags shown in Fig. 9.

The preferred embodiment of the identification tag 10 (Fig. 4), is composed of two discs 11 and 12 of substantially the same size and adapted to be permanently secured to each other. The discs 11 and 12 have a half groove or slot 14 extending from their edge to a point near the center thereof, the groove being of sufficient width and depth to accommodate the flattened ends 15 of the key holder 16. A catch lug 17, (Fig. 2) considerably less in width than the width of the slot and approximately a right angle triangle in outline is disposed at approximately the center of the slot 14 in one of the discs with its sloping side 18 pointing toward the opening of the slot at the edge of the disc.

The other disc 12 has a depression 19 on its inner face at a point directly opposite the catch lug 17 on the disc 11 when the discs are fastened together.

The disc 12 is of slightly larger diameter than the disc 11, and is provided with a projection 13 around one edge thereof into which the disc 11 is received with a tight frictional fit. To secure the two discs permanently together, the disc 11 is driven or swaged in the projection 13 of the disc 12.

A hole is drilled through each of the discs 11 and 12 and these holes register when the discs are fastened together forming a hole 23 through which a key ring or chain 24 may be passed to hold the tag on the key ring.

To attach the identification tag to a key the key is first slipped onto the holder 16, it being assumed that the ring is not attached to the tag. The ends 15 of the ring 16 are

then pressed together and pushed into the slot 14 formed in the discs 11 and 12. As the ends 15 of the ring 16 are forced into the slot 14 they slide over the sloping side 18 of the catch lug 17 and are forced toward the disc 12 and into the depression 19 in the disc 12. When the registering holes 15^a in the ends 15 of the ring come opposite the lug 17, the ends 15 spring or snap over the lug and lie wholly within the slot 14, the catch lug 17 passing through the holes 15^a and securely retaining the holder 16 against withdrawal. The identification tag is then locked to the key and cannot be removed from the same.

Any desired characters or color may be applied to the center portion 21 of the tag to facilitate identification of the particular key or a color 10^a (Fig. 9) may be applied 20 to the annular portion 20 in the discs for ornamentation and identification.

In Figs. 5, 6, 7, and 8 another embodiment of the identification tag is shown. In this embodiment a disc 25 has a hole 26 through 25 its center and a slot 27 completely across one face 28, adapted to snugly receive the ends 29 of the cover plate 30. A second slot 31 in the center of the slot 27 and at one side only of the disc and deeper and narrower 30 than the slot 27 is adapted to receive the ends 32 of the holder 33. Two catch lugs 34 at the sides of the slot co-operate with notches 32^a to lock the holder to the tag similarly to the manner already described. 35 A depression 35 on the inner face of one end 29 of the cover plate 30 receives the ends 32 of the ring 33 when they are pushed past the catch lugs 34.

A central boss 36 on the cover plate fits 40 tightly in the hole 26 of the disc 28 to hold the two parts of the tag together with the ends in the slots 27. The face 37 of the boss 36 lies in the same plane with the rim 38 of the disc 28 when the cover plate is in position and the face 39 of the cover plate 30 lies 45 in the same plane with the rim 40.

A hole 41 through both the disc 28 and the cover plate 30 on the side opposite the catch lugs 34 and the depression 35 provides 50 a means to attach the tag to a key ring or chain.

The faces 39 and 37 may be provided with identification symbols and if desired color may be applied to the depressions on each 55 side between the outer rim and the faces 37 and 39 of the cover plate 30.

When desired the identification tag may be permanently attached to the key ring as well as to the key. One method of such attachment is shown in Fig. 14 in which a notch 43, large enough to accommodate half the connecting pin or link 42^a of the ball chain 42, is cut in the top of the inner side of each disc 11 and 12 forming the identification tag 10 between the hole 23 and the

edge of the tag to allow one of the connecting links 42^a to be locked between the discs forming the tag with one of the balls in the hole 23, when discs are fastened together.

A number of keys with permanently attached identification tags may be carried together by means of the key ring, 44 illustrated in Fig. 9. This key ring comprises a lower disc 45 (Fig. 10) with a plurality of hemispherical depressions 46 a little 70 larger than the balls of the chains 42 disposed around the edge thereof each depression having a slot 47 large enough to allow the balls of the chain 42 to slip into it and deep enough so that the terminal balls 48 of the chain 42 may be centered in the spherical depression 46. A terminal ball 48 of larger diameter than the other balls of the chain, is attached to the upper end of each chain 42, and is of the same diameter as the depression 46 in the disc 45 and adapted to be seated therein with the chain 42 suspended through the slot 47 as clearly shown in Fig. 13.

A retaining disc 49 is rotatably attached 90 to the disc 45 by a rivet 50 passing through the center of both discs. A circular groove 51 of semicircular cross section is disposed on the lower face of the retaining disc 49 and when the two discs are attached together 95 in the manner indicated the groove 51 is directly above the hemispherical depressions 46 so that a ball 48 seated in one of the depressions 46 extends up into the groove 51 and the disc 49 is free to rotate with respect 100 to the other disc 45, the ball 48 remaining in the seat 46 and slipping in the groove 51. A hole 52 through the disc 49 opens directly into the groove 51 and provides a means 105 whereby any ball 48 may be raised up from its seat when the hole 52 is in registry therewith. A slot 53 of the same width as the slot 47 in the disc 45 opens into the hole 52 and provides a means of removing the chain from the discs when the slots in the upper 110 and lower discs are aligned (Fig. 9).

A key 56, may be permanently attached to the identification tag 10 in the manner already described and the chain 42 then attached to the key holder 44 by turning the 115 discs 45 and 49 with respect to each other until the slot 53 has been aligned with one of the slots 47 at which time the chain 42 may be slipped into the slots and the ball 48 seated in the corresponding seat 46. The 120 discs may then be turned again so that the slots 53 and 47 are out of alignment when it will be found impossible to remove the ball 48 as the top of the groove 51 holds it against the seat 46. A locking lug 54 may 125 be pivoted to one of the discs 45 or 49 to co-operate with a slot 55 in the other disc to lock the discs in closed position and prevent relative rotation of the discs and accidental displacement of any of the chains 42.

Any number of chains with keys attached may be fastened in this manner to the key holder depending on the number of seats which can be fitted around the circumference of the disc.

5 While the key ring shown in Fig. 9 has been described as having permanently attached identification tags 10 it will be understood that the keys may be secured to the 10 chains 42 in any desired manner.

It will be understood that other modifications and changes may be made without departing from the spirit of my invention or the scope of the appended claims and while 15 I have shown my identification tag as particularly applicable to keys it may also be used in connection with suit cases, trunks or any other object upon which it is desirable to have identifying means.

20 I claim:

1. In an identification tag, two disc shaped body members attached together, said body members having a slot on their inner faces, a catch lug in said slot, an attaching loop 25 having substantially parallel end portions each having a hole near the end thereof, means to retain said catch lug with the holes in said end portions to permanently attach said loop between said body members.

30 2. In an identification tag, two flat body members attached together, said members having a slot in the inner faces thereof, and one of said body members adapted to be covered by said other body member, an attaching loop and means to permanently

hold the ends of said loop against withdrawal when said ends are pushed into said slot.

3. In an identification tag, a flat disc, having a slot in one face extending from the edge to the point near the center thereof, a catch lug in said slot, an attaching loop having elongated flattened substantially parallel ends, said ends thereof, having a hole in each near the end thereof, a second disc 40 of substantially the same diameter as said first disc attached to said first disc to cover said slot, said second disc having a recess adjacent the catch lug in said first disc adapted to guide the ends of said loop past said catch lug when said ends are pushed into said slot and to insure the lying of said ends flatly against the bottom of said slot whereby said catch lug extends through the holes in the ends of said loop and permanently holds 45 said loops against withdrawal, and identification means applied to the outer surfaces of said discs.

4. An identification tag comprising a flat body member adapted to carry an identification symbol thereon, a second member secured to said first member and forming a slot therebetween, a catch lug extending from one of said members into said slot and a loop 50 secured to said body members, having a flattened end with a hole therein engaging said catch lug.

In testimony whereof I have affixed my signature to this specification.

REUEL H. THAYER.
